UNITED STATES PATENT OFFICE.

ANDREW L. HENRY AND GILES S. MOORE, OF INDIANAPOLIS, INDIANA, ASSIGNEES
TO TROLLEY SHOE-WHEEL COMPANY, OF INDIANAPOLIS, INDIANA, A CORPORATION OF INDIANA.

TROLLEY.

Application filed February 16, 1928. Serial No. 254,754.

Our present invention relates to contact plates for securing a good electrical connection between a trolley shoe and its supporting harp, and it is an object of the invention 5 to provide a set of contact plates which will afford a better electrical connection between the harp and shoe than has heretofore been obtained and which will thus permit an uninterrupted flow of electric current, all as 10 will be hereinafter more particularly described and claimed.

Referring to the accompanying drawings which are made a part hereof and on which similar reference characters indicate similar 15 parts,

Figure 1 is a side elevation illustrating the application of our device with portions broken away to more clearly show the construction,

20 Figure 2, a section on the line 2—2 of Fig. 1, and

Figure 3, a perspective of the spring contact plates.

In the drawings reference character 10 25 indicates a harp having forks 11 which support a pin 12 in their upper ends which pin forms a pivot or bearing for a trolley shoe 13. The harp 10 and shoe 13 may be of ordinary construction but we have shown the 30 shoe of a type illustrated in our application filed February 25, 1927, Serial No. 170,968, now Patent No. 1,698,591, dated January 8, 1929. Instead of providing independent contact plates mounted one on each side of 35 the shoe by means of rivets or the like and which frictionally engage the forks of the harp as in previous constructions, we provide two pairs of oppositely acting contact plates provided with intermediate body portions 14 and 15 and with end portions bent laterally 40 therefrom on the same sides of the bodies and form outer and inner contact plates 16 and 17. The contact plates 16 are divergent with reference to their central body portion and 45 the contact plates 17 are convergent relative thereto. The member 14 is placed within the member 15 and fastened thereto by means of rivets 18 as shown. With this assembly we have a rectangular body from each side of 50 which extend upwardly at divergent angles two contact plates 16 and 17. The contact plates 16 and 17 are of spring metal and have respectively apertures 19 and 20 of a size corresponding to the pin or bearing 12 for 55 receiving the same when the parts are assem-

bled. When the contact plates are compressed and applied between the harp and shoe the outer contact plates 16 engage the forks of the harp and the inner contact plates 17 press inwardly against the shoe 13 so that 60 as the shoe moves along a trolley wire W and oscillation between the harp and shoe occurs a good contact will be had and an uninterrupted flow of current between the harp and the wire will be maintained.

65 While we have shown our invention as applied to a particular form of trolley shoe it may be used with shoes of other construction and it will be obvious to those skilled in the art that various changes may be made in our device without departing from the spirit of the invention, and we, therefore, do not limit ourselves to what is shown in the drawings and described in the specification, but only as set forth in the appended claims.

Having thus fully described our said invention, what we claim as new and desire to secure by Letters Patent, is:

1. Means for providing permanent electric contact between a trolley shoe and harp for permitting the uninterrupted flow of the electric current comprising a body having a pair of diverging contact plates adapted to bear resiliently outward against forks of a harp, and a second body fixed to the first body 80 and having a pair of converging spring contact plates adapted to bear inwardly against a trolley shoe, substantially as set forth.

2. The combination of a pair of members disposed in fixed spaced relation, a pin connecting said members, an intermediate member on said pin between said fixed spaced members, and a pair of connected diverging spring contact plates between the intermediate member and one of the spaced members 90 for maintaining electrical contact between the spaced members and the intermediate member, substantially as set forth.

3. The combination of a pair of members disposed in fixed spaced relation, a pin connecting said members, an intermediate member on said pin between said fixed spaced members, and a pair of connected diverging spring contact plates between each side of the intermediate member and the spaced members 100 for maintaining electrical contact between the spaced members and the intermediate member, substantially as set forth.

4. The combination of a pair of fixed spaced members, a pin connecting said mem- 110

bers, an intermediate member on said pin between said fixed spaced members, and means for maintaining electrical connection between the spaced and intermediate members comprising a pair of integrally connected diverging spring contact plates engaging each of the spaced members and a similar converging pair of spaced contact plates fixed to the first mentioned contact plates and resiliently pressing inwardly against the intermediate member, substantially as set forth.

5. Means for maintaining a constant electrical contact between a supporting member and a movably supported member, comprising

ing a pair of connected spring plates each having portions disposed on opposite sides of the movably supported member, one pair of said portions bearing outwardly against the supporting member, and the other pair bearing inwardly against the movable supported member, substantially as set forth.

15
20
In witness whereof, we have hereunto set our hands at Indianapolis, Indiana, this 13th day of February, A. D. nineteen hundred and twenty-eight.

ANDREW L. HENRY.
GILES S. MOORE.
